(57) CLAIM

The ornamental design for a shoe, as shown and described.

DESCRIPTION

FIG. 1 is a front bottom perspective view of a shoe showing our new design;

FIG. 2 is a bottom view thereof;

FIG. 3 is a rear bottom perspective view thereof;

FIG. 4 is an enlarged view of the claimed design shown in FIG. 1 with environment removed for clarity purposes;

FIG. 5 is an enlarged view of the claimed design shown in FIG. 2 with environment removed for clarity purposes; and,

FIG. 6 is an enlarged view of the claimed design shown in FIG. 3 with environment removed for clarity purposes.

The broken lines immediately adjacent to and surrounding the photographic area define the peripheral bounds of the claimed design and form no part thereof. The broken lines depicting the remainder of the shoe show features that form no part of the claimed design.
